UNITED STATES PATENT OFFICE.

SEVERIN J. ROGNLIE, OF MINOT, NORTH DAKOTA.

GREASE-GUN.

1,233,510.

Specification of Letters Patent. Patented July 17, 1917.

Application filed March 26, 1914. Serial No. 827,403.

To all whom it may concern:

Be it known that I, SEVERIN J. ROGNLIE, a citizen of the United States of America, residing at Minot, in the county of Ward 5 and State of North Dakota, have invented certain new and useful Improvements in Grease-Guns, of which the following is a specification, reference being had therein to the accompanying drawing.

10 This invention relates to grease guns and the principal object of the invention is to provide a grease gun which may be filled through an opening formed in the side and to provide a novel type of latch for the 15 plunger so that the plunger may move through the cylinder either by pushing the plunger or by turning it.

With the above and other objects in view, 20 the invention consists in general of certain novel constructions, combinations and arrangements of parts, as will be hereinafter fully described, illustrated in the accompanying drawings, and specifically claimed.

25 In the accompanying drawings like characters of reference indicate like parts in the several views, and:—

Figure 1 is a side elevation of the grease gun with the sleeve turned to open the side opening.

30 Fig. 2 is a section along the line 2—2, Fig. 1 with the sleeve turned to close the side opening.

Fig. 3 is an enlarged sectional view 35 through the end portion of the gun with the pawl in a position to engage the threads of the plunger.

Fig. 4 is an end elevation of the gun with the plunger shown in section.

Fig. 5 is a view similar to Fig. 4 with the 40 collar turned in a position to bring the pawl out of engagement with the plunger rod.

Fig. 6 is a fragmentary perspective view 45 of the end of the grease gun with the collar removed and the plunger shown in section.

Fig. 7 is a perspective view of the pawl.

Fig. 8 is a perspective view of the collar.

Fig. 9 is a perspective view of the liner.

Fig. 10 is a fragmentary view of the cylinder.

50 Fig. 11 is a sectional view through the piston mounted upon the inner end of the plunger.

Figs. 12 and 13 show details of the plunger feed mechanism.

55 Referring to the drawings it will be seen that this invention comprises a cylinder 10

which is provided with a longitudinally extending opening 11 which is closed by a sleeve 12 provided with a longitudinally extending opening 13 of the same width as the opening 11 but of less length. It should be noted that the ends of the opening 11 are elongated curves so that the plunger will slide past the opening without being rolled out of shape. The sleeve 12 is mounted 60 upon the cylinder 10 between the enlarged ends 14 and 15 and is provided with the roughened strips 16. The enlarged end portions 14 and 15 are also roughened as will be seen in Fig. 1 so that by grasping the end 14 with one hand and grasping the roughened strips 16 with the other hand the sleeve may readily be turned to bring the openings 11 and 13 into and out of registry.

A neck 17 extends from the enlarged end 14 and is provided with a longitudinally extending slot 18 from the opposite sides of which there extends grooves 19 which form pivot bearings.

A liner 20 is fitted within the neck 17 80 and is provided with a notch 21 formed in alignment with the slot 18. The pawl shown in Fig. 7 is provided with the thickened portion 22 from which there extends the pivot pin 23 and is provided with the thickened 85 end portions 24 and 25, the end portion 24 forming a bearing by means of which the pawl may rock upon its pivots and the end 25 forming claws which engage the threads 90 of a plunger which will be hereinafter described. Grooves 26 are formed near the end 25 in the opposite face of the pawl and form seats in which the outer end portion 27 of the spring fits. This spring passes through the end 14 and has its inner end 95 portion bent to form an extension which is seated in the groove 28 formed in the liner 20.

A threaded plunger 29 passes through the liner 20 and has its inner end passing 100 through the center of the compressing ring 30. It should be noted that the compressing ring is rotatably mounted upon the end of the plunger so that when the plunger is rotated the compressing disk will not rotate 105 but will be drawn through the cylinder by a straight pulling motion. A collar 31 is mounted upon the neck 17 and has its central opening cut to form a cam surface 32 and an abutment shoulder 33.

110 After the locking pawl has been placed in position with its pivot points 23 resting in

the bearings 19 and its end 25 passing through the opening 21 where it is held in engagement with the threads of the plunger by means of the spring 27, the collar 31 is placed upon the neck and the end 24 of the pawl will be held in the path of the shoulder 33 thus limiting the rotary motion of the collar in one direction. When the collar is turned in the opposite direction, the cam 10 face 32 presses the end 24 of the pawl into the slot 18, thus rocking the pawl upon its pivots and bringing the end 25 out of engagement with the threads of the plunger 29.

15 The inner end of the opening formed in the collar 31 is cut to form a shoulder 34 as is illustrated in Fig. 8 which is engaged by the outer end of the spring 27, thus limiting the rotary movement of the collar in 20 this direction. It should be understood that the groove 34' is formed upon the inner end of the collar 31 for the purpose of producing the shoulder 34 against which the spring 27 is adapted to abut.

25 It will thus be seen that although the collar is rotatably mounted that this rotary movement is limited by the shoulders 33 and 34 coming into contact with the pawl and spring. It should be noted that the liner 20 30 is provided with a flattened face 35 which extends from the inner end of the notch 21 and forms a bearing face for the pawl when the pawl is rocked to release the plunger. A washer 36 is secured to the neck 17 and 35 prevents the liner and the collar from slipping out of position when the grease gun is in use.

The opposite end of the grease gun is provided with a threaded extension 37 in which 40 there is mounted a spout 38. It is, of course, obvious that if it is desired to feed the grease very rapidly or in a large quantity that the spout may be removed and the gun used without the same.

45 When using the device the collar is turned to the position shown in Fig. 5 so that the plunger will be released from the pawl and the plunger then drawn out as far as possible. The sleeve 12 is then turned to bring 50 the openings 11 and 13 into alignment as shown in Fig. 1 and this leaves an opening through which grease may be poured or if the grease is solid may be inserted by means of a suitable paddle.

55 After the cylinder is filled with grease the sleeve is turned to close the opening 11 and the gun is then ready for use. If the grease is thin the collar is left as shown in Fig. 5 and the handle 39 of the plunger is grasped 60 and the plunger thrust into the cylinder until the desired amount of grease has been forced out through the spout 38. If the grease is thick the collar is turned to the position shown in Fig. 4 and this releases 65 the pawl so that it will engage the threads

of the plunger thus making it possible to force the plunger through the cylinder by turning it and converting the gun from a forced feed into a screw feed.

It should be noted, however, that after the 70 collar has been turned to the position shown in Figs. 3 and 4 if it is desired to force the plunger through the cylinder by a direct drive, this may be accomplished without turning the collar to the position shown in 75 Fig. 5 since the threads of the plunger can ride past the pawl. After the plunger has been driven through the cylinder the full extent it cannot be withdrawn by a straight 80 pull unless the collar is turned to the position shown in Fig. 5, thus releasing the pawl from engagement with the teeth of the plunger.

It will thus be seen that there has been provided an improved type of locking pawl 85 which is so constructed that the plunger may be thrust through the cylinder to drive out the grease when the locking pawl is in either of two positions but which will hold the plunger within the cylinder when the 90 pawl is in one position so that in order to withdraw the plunger it is necessary to turn the plunger.

The compressing ring which forms the piston for the gun comprises the plates 40 95 and 41 which are mounted upon the threaded shaft 42 having the enlarged head 43, a leather cup 30 being held between the plates. A securing nut 44 is screwed upon the shaft and holds the plates tightly in place. The 100 reduced inner end 46 of the plunger 29 is passed through the shaft 42 and the piston held thereon by the key 47. It will thus be seen that the plunger can rotate without the piston being rotated.

Having thus described the invention, what is claimed as new, is:—

1. A lubricator comprising a cylinder, a neck leading from said cylinder, and provided with a slot, a liner positioned in 110 said neck and provided with a notch registering with said slot, a threaded plunger passing through said liner, a pawl pivotally connected with said neck, a spring engaging said pawl normally holding said inner 115 end in engagement with the threads of said plunger, and a collar rotatably mounted upon said neck and having the walls of its central opening formed into a cam surface to rock said pawl out of engagement with 120 the threads of said plunger upon the turning of said collar.

2. A lubricator comprising a cylinder, a neck extending from said cylinder and provided with a slot having notches formed to 125 each side forming pivot sockets, a threaded plunger passing through said neck, a pawl mounted in said slot, pivot points carried by said pawl and positioned in said bearings, a spring carried by said cylinder and 130

- having its outer end engaging said pawl to normally hold the inner end of said pawl in engagement with the threads of said plunger, a collar mounted upon said neck and
- 5 having the walls of its central opening cut to form a cam face adapted to rock said pawl out of engagement with said plunger, said cam face terminating in an abutment shoulder adapted to contact with the outer
- 10 end of said pawl to limit the rotary motion of said collar in one direction, the inner end of said collar being cut to form an abutment shoulder adapted to contact with the end of said spring to limit the rotary movement of said pawl in the opposite direction.
- 15 3. A lubricator comprising a cylinder, a neck extending from said cylinder and provided with a longitudinally extending slot, a liner positioned within said neck and provided with a notch registering with said slot, a pawl pivotally mounted in said slot and having its inner end passing through said notch, a plunger passing through said liner and adapted to be engaged by said
- 20 pawl, a collar mounted upon said neck, and adapted to be rotated whereby to rock said pawl out of and into engagement with said plunger, and a plate surrounding said plunger and secured to the outer end of said
- 25 neck whereby said liner and collar will be held in place.
4. A lubricator comprising a cylinder, a neck extending from said cylinder and provided with an opening, a threaded plunger
- 30 passing through said neck, a pawl mounted upon said neck and normally held in a position to extend through said opening and engage said plunger, and a collar rotatably mounted upon said neck and provided with
- a cam surface engaging said pawl for moving said pawl out of engagement with said plunger upon turning said collar in one direction.
5. A lubricator comprising a cylinder, a neck extending from said cylinder and provided with an opening, a threaded plunger extending through said neck, a pawl pivotally connected with said neck and extending longitudinally thereof, resilient means normally forcing one end of said pawl through said opening and into engagement with said plunger whereby said plunger may be moved into said cylinder by turning and by pushing to cause the pawl to ride over the threads of said plunger, and means for moving said pawl out of engagement with said plunger to permit said plunger to be drawn out of said cylinder, said pawl normally preventing said plunger from being drawn from said cylinder and permitting the plunger to be removed by turning.
6. A lubricator comprising a cylinder provided with a longitudinally extending elliptical opening, a sleeve rotatably mounted upon said cylinder and provided with a longitudinally extending opening of approximately the same width and of less length than the opening of said cylinder, the end portions of the opening in said sleeve being cut square, and an expelling plunger extending into said cylinder.

In testimony whereof I hereunto affix my signature in presence of two witnesses.
